CONTROLLING PHASE RELATIONS BETWEEN STATIONS

Application filed October 19, 1927. Serial No. 227,304.

- This invention relates to methods and arrangements for maintaining the current supplied from one station over a line to a distant station in a desired phase relation. 5 More particularly, the invention has application to maintaining constant phase relations between the carrier waves of a plurality of broadcasting stations transmitting upon the same wave length. 10 When distant radio stations are connected by telephone lines so that they may broadcast the same program, it becomes desirable that all the stations use the same carrier frequency in order to reduce the number of wave lengths 15 required for the one program. Such a method of operation, however, encounters the difficulty that slight changes in the relative phases of the radio frequency currents from the various broadcasting stations affect the field 20 strength in certain localities, thus causing received signals to vary in amplitude, and in some cases to vanish completely. In accordance with the present invention, it is proposed to remedy this condition by 25 supplying a controlling current of some base frequency over wire lines to the various broadcasting stations, the common carrier wave at the various broadcasting stations being derived from or controlled by the base frequency 30 so transmitted. In order to compensate for the variation in phase produced upon the controlling or base frequency by reason of temperature or other variations of the line, a special automatic arrangement is provided 35 to produce in the line changes to compensate for the changes in phase. Specifically, the present invention contemplates controlling the phase variation by picking up waves from two radio transmitters 40 interconnected by a telephone line over which a controlling frequency is transmitted, said waves being picked up at two points in the immediate vicinity of and equi-distant from a third point so located between the two transmitters that under normal phase conditions 45 the waves from the two transmitters will annul each other therat. The waves thus picked up are then combined to produce a null effect if the two transmitters are in phase 50 with each other. If, however, the two transmitters are out of phase, the waves picked up at the two pick-up points will not produce a null effect, and this fact is taken advantage of to automatically operate the phase adjusting network in the line over which the controlling frequency is transmitted to compensate 55 for the variation in phase indicated. The invention may now be more fully understood from the following detailed description thereof when read in connection 60 with the accompanying drawing, of which Figure 1 shows curves illustrating the principles underlying the invention; Figs. 2 and 3 illustrate schematically certain types of radio antennæ; Fig. 4 shows curves indicating the 65 distribution of magnetic field strength under different phase conditions at points intermediate between two broadcasting transmitters; Fig. 5 illustrates a circuit arrangement embodying one form of the invention; and 70 Fig. 6 shows with some degree of detail the control mechanism symbolically represented in Fig. 5. As a simple illustration of varying field 75 strength let us consider two broadcasting stations symbolically represented at the points designated east and west in Fig. 1. Each station may be supposed to have a similar antenna consisting of a vertical rod with equal sources of electromotive force between the rod 80 and the ground. Under these circumstances, each antenna is surrounded by a magnetic field and an electric field, these fields decreasing in strength with increasing distance from the antenna. Only a few lines of force are 85 shown in the diagram of Fig. 1 in order to indicate the direction of certain portions of the fields. The lines marked *e* and *e'* represent lines of force of the electric field, the arrows indicating the direction. Similarly, the 90 circles marked *m* and *m'* indicate the lines of force of the magnetic field, entering and leaving the paper in a plane at right angles thereto. The circles with the crosses represent positive lines of force and the circles with the dots in the center represent negative lines of 95 force. If the currents in the several antennæ are in phase, then at the point *a* midway between the stations the magnetic flux *m* surrounding 100

the east antenna will be equal and opposite in direction to the magnetic flux m' surrounding the west antenna. The resultant magnetic field at point a is therefore equal to zero. 5 However, if the phases of the generators should differ by 180° , then at a the vectors representing the alternating magnetic fluxes would add, while at b , a point just one-quarter

10

$$I_w = A_1 \cos \left(\omega t + \frac{2\pi x}{\lambda} + \Psi_1 \right) + A_2 \cos \left(\omega t + \frac{2\pi x}{\lambda} + \Psi_2 \right) \quad (2) \quad 75$$

wave length distant from a , the fluxes would subtract. At c , one-half wave length from a , the fluxes would again add. The same holds 15 true approximately for locations within a short distance north or south of these points.

On the other hand, the individual electric

20

$$I_e = \sqrt{A_1^2 + A_2^2 + 2A_1 A_2 \cos(\Theta_2 - \Theta_1)} \cos \left(\omega t - \frac{2\pi x}{\lambda} + \Theta_3 \right) \quad (3) \quad 80$$

$$I_w = \sqrt{A_1^2 + A_2^2 + 2A_1 A_2 \cos(\Psi_2 - \Psi_1)} \cos \left(\omega t + \frac{2\pi x}{\lambda} + \Psi_3 \right) \quad (4) \quad 85$$

25 fields e and e' are a maximum when the magnetic fields m and m' are a maximum. Due to their relative directions at point a , however, the resultant of e plus e' is a maximum while 30 that of m plus m' is zero. As phase shifts occur, the location of maximum and minimum resultant electrostatic fields is changed.

It is, of course possible to devise receiving antennæ structure which will respond to the 35 magnetic fields without being substantially affected by the electric fields, and vice versa. For example, the loop type antenna such as is illustrated schematically in Fig. 2, responds mainly to magnetic fields, while the antenna of the type conventionally indicated in Fig. 40 3 responds mainly to electric fields. The majority of antennæ, however, such as L or T type antennæ, are responsive to both magnetic and electric fields.

45 With these considerations in mind, let us analyze the character of the current received where the antenna is responsive to both magnetic and electric fields and located at any given point in the vicinity of a of Fig. 1. Assuming the point a lies midway between 50 two similar transmitters, each transmitting through similar media, let x equal the distance from the point a to a receiving station near a and located on the line $c-a$ of Fig. 1. Also, let λ equal the wave length of both oscillators. 55 Then the current flowing in the receiving antenna due to waves from the east transmitter is:

$$60 \quad I_e = A_1 \cos \left(\omega t - \frac{2\pi x}{\lambda} + \Theta_1 \right) + A_2 \cos \left(\omega t - \frac{2\pi x}{\lambda} + \Theta_2 \right) \quad (1) \quad 125$$

In the foregoing equation, t is the time of transmission; ω is 2π times the frequency; 65 A_1 and A_2 are magnitude constants; and

Θ_1 and Θ_2 are phase angle constants. Also, the first term of the quantity represented by the right hand side of the equation is the current due to the magnetic field, while the second term is that due to the electric field.

The current flowing in the receiving antenna due to waves from the west station may be represented:

$$I_w = A_1 \cos \left(\omega t + \frac{2\pi x}{\lambda} + \Psi_1 \right) + A_2 \cos \left(\omega t + \frac{2\pi x}{\lambda} + \Psi_2 \right) \quad (2) \quad 75$$

in which A_1 and A_2 are again magnitude constants, which may have the same or nearly the same values as in the case of Equation (1), and Ψ_1 and Ψ_2 are phase angle constants.

These expressions may be rewritten in the form of resultant vectors, as follows:

$$I_e = \sqrt{A_1^2 + A_2^2 + 2A_1 A_2 \cos(\Theta_2 - \Theta_1)} \cos \left(\omega t - \frac{2\pi x}{\lambda} + \Theta_3 \right) \quad (3) \quad 80$$

$$I_w = \sqrt{A_1^2 + A_2^2 + 2A_1 A_2 \cos(\Psi_2 - \Psi_1)} \cos \left(\omega t + \frac{2\pi x}{\lambda} + \Psi_3 \right) \quad (4) \quad 85$$

In Equations (3) and (4), the symbols Θ_3 and Ψ_3 have the following values:

$$\Theta_3 = \tan^{-1} \frac{A_1 \sin \Theta_1 + A_2 \sin \Theta_2}{A_1 \cos \Theta_1 + A_2 \cos \Theta_2} \quad (5) \quad 90$$

$$\Psi_3 = \tan^{-1} \frac{A_1 \sin \Psi_1 + A_2 \sin \Psi_2}{A_1 \cos \Psi_1 + A_2 \cos \Psi_2} \quad (6) \quad 95$$

Now, since the phase angle constants in the foregoing equations are functions of the transmitting antennæ and the transmitting media, which are assumed to be the same for both transmission east and west, it is evident that the expressions $\cos(\Theta_2 - \Theta_1)$ and $\cos(\Psi_2 - \Psi_1)$ in Equations (3) and (4) will be equal to each other, and hence the terms under the radicals in said equations are equal. It is also evident that I_e plus I_w add up to zero whenever

$$\frac{4\pi x}{\lambda} + \Psi_3 - \Theta_3 = \pm n\pi \text{ radians} \quad (7) \quad 110$$

where n is any odd number. It follows, therefore, that at points approximately midway between the broadcasting stations a change in Θ_3 or Ψ_3 will cause the total received current to vary or even to disappear.

Varying field strength may be eliminated by keeping the oscillators at the two transmitting stations in perfect synchronism. If, instead of using oscillators, the carrier wave is provided at each station by means of harmonic generators of radio frequency driven

or controlled by the same fundamental controlling current (preferably of voice frequency) transmitted over a telephone line 130

between the stations, the phase relation between the two radio currents will be constant, provided the phase relation between the fundamental controlling currents at the sending and receiving ends of the telephone line is constant.

Fig. 5 illustrates an arrangement for maintaining the constant phase relation between two or more radio sending stations. In order to understand the principles underlying this arrangement, however, it is desirable to enter further into certain theoretical considerations.

Referring to the curves of Fig. 4, the curve A is so plotted that its ordinates show the amplitude of the magnetic field component along the line $a-b-c$ located approximately midway between the two radio broadcasting stations considered in connection with Fig. 1. Curve A shows that the points of maximum field strength are approximately one-half wave length apart. This is evident from a consideration of Equations (1) and (2) above given, which show that the portion of the antenna current due to the resultant magnetic fields is proportional to

$$\begin{aligned}
 M &= \cos \left(\omega t - \frac{2\pi x}{\lambda} + \Theta_1 \right) + \cos \left(\omega t + \frac{2\pi x}{\lambda} + \Psi_1 \right) \\
 &= \cos \omega t \cos \left(-\frac{2\pi x}{\lambda} + \Theta_1 \right) - \sin \omega t \sin \left(-\frac{2\pi x}{\lambda} + \Theta_1 \right) \\
 &\quad + \cos \omega t \cos \left(\frac{2\pi x}{\lambda} + \Psi_1 \right) - \sin \omega t \sin \left(\frac{2\pi x}{\lambda} + \Psi_1 \right) \\
 &= \left\{ \cos \Theta_1 \cos \left(-\frac{2\pi x}{\lambda} \right) + \sin \Theta_1 \sin \frac{2\pi x}{\lambda} \right\} \cos \omega t \\
 &\quad + \left\{ \cos \Psi_1 \cos \frac{2\pi x}{\lambda} - \sin \Psi_1 \sin \frac{2\pi x}{\lambda} \right\} \cos \omega t \\
 &\quad - \left\{ \sin \left(-\frac{2\pi x}{\lambda} \right) \cos \Theta_1 + \cos \left(-\frac{2\pi x}{\lambda} \right) \sin \Theta_1 \right\} \sin \omega t \\
 &\quad - \left\{ \sin \frac{2\pi x}{\lambda} \cos \Psi_1 + \cos \frac{2\pi x}{\lambda} \sin \Psi_1 \right\} \sin \omega t
 \end{aligned} \tag{8}$$

Now, bearing in mind that in Equations (1) and (2) x represents the distance from the midpoint between the two transmitters to any assumed pick-up or receiving point, it becomes evident that if we let x equal zero in the final expression for M given by Equation (8), we will then have the value of the magnetic field at the point a of Figs. 1 and 4, which is:

$$M_a = (\cos \Theta_1 + \cos \Psi_1) \cos \omega t - (\sin \Theta_1 + \sin \Psi_1) \sin \omega t \tag{9}$$

So, also, if we let x equal $\frac{\lambda}{4}$ in equation (8), we obtain the value of the magnetic field at the point b of Fig. 4, which is:

$$M_b = (\sin \Theta_1 - \sin \Psi_1) \cos \omega t + (\cos \Theta_1 - \cos \Psi_1) \sin \omega t \tag{10}$$

Now, if we assume that the phase angle constants Θ_1 and Ψ_1 are both multiples of 2π , then

Equations (9) and (10) reduce to:

$$M_a = 2 \cos \omega t \tag{11}$$

$$M_b = 0 \tag{12}$$

As Equation (11) is the expression for the maximum value of the field strength, whereas Equation (12) represents the minimum condition, it is evident that the field strength varies from zero to a maximum value within the distance of a quarter wave length, and that hence the points of maximum field strength are approximately one-half wave length apart, as previously stated.

The curve B of Fig. 4 shows the amplitude of the magnetic field at points along the same line ($a-b-c$) after the relative phase between the two transmitting stations has shifted a fraction of a period P . The distance which the curve A would have to be displaced in order to coincide with B is $\frac{P\lambda}{2}$.

For example, suppose $P = \frac{1}{2}$ corresponding to a phase shift of 180° . Then the curve A would be shifted $\frac{\lambda}{4}$ so that wherever a max-

$$\left. \begin{aligned}
 & \cos \Theta_1 \cos \left(-\frac{2\pi x}{\lambda} \right) + \sin \Theta_1 \sin \frac{2\pi x}{\lambda} \\
 & \cos \Psi_1 \cos \frac{2\pi x}{\lambda} - \sin \Psi_1 \sin \frac{2\pi x}{\lambda}
 \end{aligned} \right\} \cos \omega t \tag{8}$$

imum amplitude previously occurred there would now be zero amplitude.

It is obviously desirable that the phase shift P be kept as small as possible, or, in other words, that the phase relation of the two stations be maintained substantially constant. This result may be accomplished by the arrangement shown in Fig. 5. Here two radio transmitting stations, RT and RT',

are conventionally indicated, these radio stations being interconnected by a telephone line L over which a base or controlling frequency, supplied by a source S, may be trans-

mitted. At each radio transmitter it is understood that the conventional symbol will

include suitable means by which the common carrier wave employed at the two stations may be derived from or controlled by the frequency transmitted over the line L. This may be accomplished, for example, by the use of harmonic generators of a well-known type. The line L includes, at some point near the middle thereof, a phase shifting network PN, by the adjustment of which the phase of the controlling current transmitted over the line 10 L may be maintained the same at the station RT' as at the station RT. When this condition occurs, it follows that the derived carrier waves will also be in phase at both stations.

15 In order to automatically control the phase shifter PN, loop antennæ 1 and 2 are located at points such as d and e of Fig. 4, these points being equidistant from and on either side of a point at which, under normal conditions, the magnetic components of the wave from the two transmitters will neutralize each other. The voltages induced in these antennæ will be equal since the ordinates d—f in Fig. 4 are equal to the ordinates e—g. It is also evident that a slight change of phase P will cause unequal voltages to be induced in the two antennæ, as is indicated by the fact that the ordinates e—h in Fig. 4 are 20 greater than the ordinates d—k, when the curve is shifted to the position represented by the curve B.

Each antenna is connected to receiving sets R₁ and R₂, conventionally indicated in the 35 diagram of Fig. 5. These receiving sets may be of any type well known in the art and function to translate the received waves picked up by the two antennæ into voice frequency currents, which may be transmitted 40 over short lines L₁ and L₂, of equal length, to a common point adjacent the line L.

The currents transmitted over the lines L₁ and L₂ are then passed through transformers 3 and 4 to a detector arrangement comprising 45 two vacuum tubes 5 and 6, which are connected to a polar relay PR, said polar relay operating a control mechanism symbolically indicated in the diagram of Fig. 5 but illustrated in somewhat more detail in Fig. 6.

50 If we assume that the voltages in the antennæ 1 and 2 are equal, then the radio receiving sets R₁ and R₂ and the lines L₁ and L₂ will be adjusted so that the current I₁ flowing in the upper winding of the polar 55 relay PR will be just equal to the current I₂ flowing in the lower winding thereof. Under these conditions, the relay armature will be in neutral position. Should the voltages induced in the antennæ become unequal, due 60 to a phase shift P in waves radiated from the two transmitters, as explained above, the resulting inequality in the currents I₁ and I₂ would operate the armature of the polar relay in one direction or the other, depending 65 upon the direction of the phase shift.

Referring to Fig. 6, if the armature of the relay PR be shifted to its upper position the relay 7 will be energized to cause the motor M to rotate in one direction. If the armature of the relay is shifted to its lower contact the relay 8 becomes energized and causes the motor M to rotate in the opposite direction. The shaft of the motor M may be geared in any suitable manner to adjust the phase shifting network PN until the two transmitting stations are again brought into synchronism, when the armature of the relay PR will again be in neutral position. In this manner, the condition of synchronism between the two stations is automatically maintained.

70 It will be understood that the controlling mechanism specifically illustrated in Fig. 6 is merely disclosed for purposes of illustration, it being obvious that any other known form of controlling mechanism may be employed. Likewise, the phase shifting network PN is merely indicated symbolically, it being understood that any well-known type of phase shifter may be automatically adjusted by suitable control mechanism.

75 It will be obvious that the general principles herein disclosed may be embodied in many other organizations widely different from those illustrated without departing 80 from the spirit of the invention as defined in the following claims.

85 What is claimed is:

1. In a system in which a plurality of radio transmitters operating upon a common wave length are interconnected by a wire line including a phase controlling element, said line transmitting a fundamental controlling frequency to determine the radio wave length employed; the method of maintaining a constant phase relation between any two stations so interconnected, which consists in picking up waves at two pick-up points close to but equidistant from a nodal point at which the combined waves from the two stations will substantially annul each other under normal phase conditions, combining said waves to produce a null effect under normal phase conditions and to produce an effect determined by phase variation under abnormal conditions, and adjusting the phase controlling element of the interconnecting line to compensate for the indicated phase variation.

90 110 115 120 125 130

2. In a system in which a plurality of radio transmitters operating upon a common wave length are interconnected by a wire line including a phase controlling element, said line transmitting a fundamental controlling frequency to determine the radio wave length employed; the method of maintaining a constant phase relation between any two stations so interconnected, which consists in picking up waves at two pick-up points close to but equidistant from a nodal point at which the combined waves from the two stations will

substantially annul each other under normal phase conditions, transmitting the waves picked up over similar circuits to a common point, combining the waves at said common point to produce a null effect under normal phase conditions and to produce an effect determined by phase variation under abnormal conditions, and automatically controlling the adjustment of the phase controlling element of the interconnecting line to compensate for the indicated phase variation.

3. A system including a plurality of radio transmitters operating upon a common wave length, a wire line interconnecting a pair of said transmitters, means to transmit a fundamental controlling frequency over said wire line, means at each transmitter to determine from said frequency the wave length employed by the transmitters, means to pick up waves from said transmitters at two pick-up points close to but equidistant from a nodal point at which combined waves from the two stations will substantially annul each other, means to combine said waves to produce a null effect under normal phase conditions and to produce an effect determined by phase variation under abnormal conditions, and a phase controlling element for the interconnecting line adjustable to compensate for the indicated phase variation.

4. A system including a plurality of radio transmitters operating upon a common wave length, a wire line interconnecting a pair of said transmitters, means to transmit a fundamental controlling frequency over said wire line, means at each transmitter to determine from said frequency the wave length employed by the transmitters, means to pick up waves from said transmitters at two pick-up points close to but equidistant from a nodal point at which combined waves from the two stations will substantially annul each other, electrically similar circuits for transmitting the waves picked up at the two pick-up points to a common point, means at said common point to combine the waves to produce a null effect under normal phase conditions and to produce an effect determined by phase variation under abnormal conditions, and a phase controlling element for the interconnecting line adjustable to compensate for the indicated phase variation.

5. A system including a plurality of radio transmitters operating upon a common wave length, a wire line interconnecting a pair of said transmitters, means to transmit a fundamental controlling frequency over said wire line, means at each transmitter to determine from said frequency the wave length employed by the transmitters, means to pick up waves from said transmitters at two pick-up points close to but equidistant from a nodal point at which combined waves from the two stations will substantially annul each other, electrically similar circuits for transmitting

the waves picked up at the two pick-up points to a common point, means at said common point to combine the waves to produce a null effect under normal phase conditions and to produce an effect determined by phase variations under abnormal conditions, a phase controlling element for the interconnecting line, and means operated by said combining means to automatically adjust said phase controlling element to compensate for the indicated phase variation.

In testimony whereof, I have signed my name to this specification this 18th day of October, 1927.

HARRY NYQUIST.
